(57) **CLAIM**

The ornamental design for a cabin for vehicles, as shown and described.

DESCRIPTION

The patent or application file contains at least one drawing executed in color. Copies of this patent or patent application publication with color drawing(s) will be provided by the Office upon request and payment of the necessary fee.

1. Cabin for vehicles

1.1 is a rear and left-side perspective view of a cabin for vehicles embodying my new design;

1.2 is a partial and enlarged left-side perspective view thereof;

1.3 is a top, rear, and left-side perspective view thereof;

1.4 is a partial and enlarged front perspective view thereof;

1.5 is a partial and enlarged front and right-side perspective view thereof;

1.6 is a top plan view thereof;

1.7 is a top, front, and right-side perspective view thereof;

1.8 is a top, front, and left-side perspective view thereof;

1.9 is a rear perspective view thereof with the liftgate opened;

1.10 is a rear perspective view thereof with the liftgate and door opened;

1.11 is a rear perspective view thereof with the liftgate opened; and

1.12 is a rear perspective view thereof.
